A. J. Murphy, ATTORNEY

UNITED STATES PATENT OFFICE.

JESSE ALEXANDER, OF NEW YORK, N. Y.

TYPE-WRITING-MACHINE LINE-SPACING MECHANISM.

Specification of Letters Patent. Patented May 22, 1917.

1,227,519.

Original application filed May 22, 1912, Serial No. 698,879. Divided and this application filed March 20, 1915. Serial No. 15,754.

To all whom it may concern:

Be it known that I, JESSE ALEXANDER, a citizen of the United States of America, and residing at New York, in the county of Kings and State of New York, have invented new and useful Improvements in Type-Writing-Machine Line-Spacing Mechanism, of which the following is a specification.

10 The present invention relates to line spacing mechanism for typewriters and the objects of the invention are to provide simple and effective means for advancing the paper-carrying platen one or a number of 15 line spaces, as may be required.

15 A special object is to make possible the line-spacing operation from either end of the platen.

According to my invention, separate and 20 independent line spacing devices are provided, one at each end of the platen. These devices are preferably duplicates of each other, each consisting in general of a spring 25 pressed lever carrying a pawl for engagement with a ratchet at the end of the platen and an adjustable cam device which controls the point of engagement of the pawl with the ratchet and thereby governs the extent of feed.

30 Other features will appear as the specification proceeds.

The accompanying drawing illustrates my invention embodied in a preferred form but I would have it understood that changes 35 and modifications may be made without departing from the true scope and spirit of the invention.

Figure 1, is a front view of a typewriter carriage constructed in accordance with and 10 embodying the invention, the central portion of the carriage shown broken away.

Fig. 2, is a view of the left-hand end of the carriage, with the end plate of the carriage frame partly broken away to expose 15 the operating lever, ratchet and brake roller.

Fig. 3, is a view of the opposite end of the carriage, showing the operating lever pushed back at the end of its line feeding movement.

50 Fig. 4, is a broken sectional view of the right-hand end of the carriage taken substantially on the plane of line 4, 4 of Fig. 3.

Fig. 5, is a perspective view of the operating lever, ratchet and cam lever.

55 The carriage is of suitable construction,

preferably such as disclosed in my application filed May 22nd, 1912, Serial No. 698,879 of which the present case is a division. This carriage consists in general of a frame made up of end plates 7 and 8 connected by front 60 and back bars 9 and 10, and a platen 11 carried by a shaft 12 journaled in the end plates. The usual finger knobs 13 are provided on the ends of the platen roll shaft. Suitable paper guides are provided, the introductory paper guide being indicated at 14.

A separate line spacing device is provided at each end of the platen so that the line spacing can be effected from either end. 70 These line spacing devices are preferably duplicates of each other and in the form shown consist of operating levers 20 pivoted on the platen shaft at opposite ends of the platen and carrying pawls 21 to engage 75 ratchets 22 fixed on the shaft at the ends of the platen. The operating levers are provided with upwardly projecting finger extensions 23 and said levers are normally 80 pressed forwardly by the springs 24 coiled about the shaft, engaging lugs 25 on the levers at one end and having their other ends 26 anchored in the end plates 7-8. The forward movement of the operating 85 levers is limited by engagement of the lugs 27 on the levers with shoulders 28 on the carriage end plates and similarly the reverse or feeding movement of the levers is limited by engagement of lugs 29 on the levers with shoulders 30 on the end plates. 90

The feed pawls 21 are pivoted at 33 on outstanding lugs 34 on the levers and are pressed toward the ratchets by the springs 35. These pawls are provided with angular 95 downwardly extending portions 36 adapted to be engaged by cam surfaces 37 on the members 38 which are pivoted on the shaft outside the carriage end plates. The cam tracks 37, by engagement with the angular extensions 36 of the pawls hold the pawls 100 elevated out of engagement with their ratchets. In the rearward or feeding movement of the operating levers the pawl extensions will pass from engagement with the cam tracks and thereby allow the pawls to 105 drop into engagement with the ratchets whereupon the movement of the levers will then be imparted to the ratchets and hence to the platen fixed therewith.

The point of engagement of the pawls 110

with the ratchets and hence the extent of feed or line spacing imparted to the platen is determined by shifting the cam members so that the pawls will engage the ratchets 5 at an earlier or a later period in the course of movement of the levers. The pivoting of the cam members on the platen shaft permits of this adjustment and the cam members may be held in adjusted position by 10 providing them each with a pin or stud 40 to engage in one of a series of openings 41 in the adjacent end plate. The adjustment of the cam members may be confined within desired limits by providing limiting stops 15 42 on the end plates.

The platen may be held in the position to which it has been turned by means of a 20 brake roller 45, held yieldingly against one of the ratchets by a spring arm 46. The platen may be freed from the restraint of this brake roller by means of a releasing lever 47 pivoted to the end plate at 48 and notched at 49 at its rear end to engage the pivot stud 50 of the roller to force said 25 roller away from the ratchet.

My invention renders it possible to line-space the platen with either or both hands, as may be convenient. The spacing can be readily changed by simply setting the cam 30 members at different points. The two line spacers may be set for different spacing so that when one spacing is required the device which is set for that spacing will be operated and when a different spacing is 35 required, the other spacer will be operated. The parts are all simple and inexpensive and may for the most part be made of sheet metal, the operating lever for instance being made from a flat plate with the several 40 lugs bent up at the edges thereof and the upper end twisted as shown to provide the finger hold.

The ratchets at the opposite ends of the platen roll may have different numbers of 45 teeth, as indicated. This provides for further variations in the line spacing of the platen.

What I claim is:—

1. In a typewriter line spacing device, a 50 carriage end plate, a platen shaft rotatable

therein, a platen mounted on said shaft, a spring pressed spacing lever pivoted at one side of the carriage plate, an adjusting lever pivoted at the opposite side of the carriage plate, a ratchet secured on the end of the 55 platen, a spring pressed pawl pivotally mounted on the spacing lever for engagement with said ratchet and provided with an extension projecting across to the opposite side of the carriage plate into the plane 60 of the adjusting lever thereat and stops limiting the extent of movement of the spacing lever.

2. In a typewriter line spacing device, a carriage end plate, a platen shaft rotatable 65 therein, a platen mounted on said shaft, a spring pressed spacing lever pivoted at one at the opposite side of the plate, a ratchet side of the carriage plate, an adjusting lever pivoted at the opposite side of the carriage 70 plate, a ratchet secured on the end of the platen, a spring pressed pawl pivotally mounted on the spacing lever for engagement with said ratchet and provided with an extension projecting across to the opposite 75 side of the carriage plate into the plane of the adjusting lever thereat, a stop lug on the spacing lever extending across the top of the carriage plate and shoulders on said carriage plate arranged for engagement by said 80 lug to limit the movement of the spacing lever.

3. In a typewriter line spacing device, a carriage end plate, a platen shaft rotatable 85 therein, a platen on said shaft, a ratchet on the end of said platen, a spacing lever pivoted at the inside of the carriage plate along side said ratchet, a spring pressed pawl pivoted on said spacing lever having a tooth extending laterally into engagement with 90 the teeth of the ratchet and an angular portion extending across the top of the carriage plate and an adjusting lever pivotally supported at the outside of the carriage plate having a portion extending above the top 95 of the carriage plate and into the path of movement of the angularly extending portion of the spring pressed pawl.

JESSE ALEXANDER.
